DESIGN FOR A HANDLE FOR ELECTRIC IRONS AND THE LIKE

William J. Russell, Mansfield, Ohio, assignor to
Westinghouse Electric & Manufacturing Com-
pany, a corporation of Pennsylvania

Application February 21, 1942, Serial No. 105,947

Term of patent 14 years

To all whom it may concern:

Be it known that I, William J. Russell, a citizen of the United States, residing at Mansfield, in the county of Richland and State of Ohio, have invented a new, original, and ornamental Design for a Handle for Electric Irons and the like, of which the following is a specification, reference being had to the accompanying drawing, forming part thereof, in which:

Figure 1 is a perspective view taken from the front and above of the handle for electric irons and the like showing my new design, the con-

cealed side of the handle being like the side illustrated;

Fig. 2 is a view in perspective taken from the rear and above showing my new design; and

Fig. 3 is a perspective view taken from the front and above showing my new design.

I claim:

The ornamental design for a handle for electric irons and the like, substantially as shown and described.

WILLIAM J. RUSSELL,
